UNITED STATES PATENT OFFICE

VICTOR E. FLODIN, OF OAK PARK, ILLINOIS, ASSIGNOR TO CRANE CO., OF CHICAGO, ILLINOIS, A CORPORATION OF ILLINOIS

MILLING MACHINE

Application filed April 9, 1928. Serial No. 268,485.

This invention pertains to milling machines and the like, although it has more particular reference to a mechanism primarily adapted to mill-out or machine parallel grooves or slots along the interior walls of a hollow body. The invention is peculiarly useful in connection with the manufacture of gate valves of the type described and claimed in my co-pending application Serial No. 268,484, filed April 9, 1928, which use will be more fully described hereinafter for the purpose of illustration only.

Considering the ordinary gate valve, the body, whether cast, forged or otherwise formed, is usually provided with one or more guide ribs, slots or grooves, on each side, for guiding the gate in its movements to and from its seating position. The gate itself, for such purpose, is likewise provided with a cooperative rib or ribs, groove or grooves, on each side, as the case may be, for engagement with or in the ribs, slots or grooves provided in the body.

Though many attempts have been made, I am aware of no attempt of a successful nature to fit the guides on the gate and body to or with one another in an extremely accurate manner. The problems encountered in doing so have been several, although one of the primary problems perhaps is the difficulty and expense of the necessary machining operations and the mating of parts thereafter. On the contrary, the almost invariable practice has been to machine the guides or guide surfaces on the gate or disc in a more or less superficial way, leaving the cooperative surfaces on the body rough while allowing sufficient clearance between the guides on the gate and body to permit raising and lowering of the gate in the body without rubbing engagement of the cooperative guide surfaces.

In most cases a single guide rib is placed on each side of the valve body and one of such ribs is made considerably wider laterally than the other so that the gate, which has its guide slots milled out proportionately to receive the ribs, may be inserted in the valve body in but one position. Sometimes, however, manufacturers have disposed

the guide ribs unsymmetrically in the body to obtain the same result, and then too, there are instances, even where the guide ribs have been disposed symmetrically in the body, the methods of machining or fitting have not permitted reversibility in seating the gate or disc because of what have heretofore been thought to be insurmountable, inherent inaccuracies; thus, for example, when repair gates or discs have been ordered it has been necessary in a large proportion of the cases to have the body as well as the gate on hand in order to fit them properly, and the downstream face and upstream face, pressure side of the gate or disc, must necessarily match their respectively cooperative faces in the body.

However, with such construction, wear on the parts is inevitably considerable, and therefore extremely objectionable. With any difference of pressures on opposite sides of the gate, the gate will be forced toward the side of least pressure during its opening and closing movements which will in turn cause rubbing of the seat surfaces and guide surfaces and the rapid wearing away of both whether or not the guide surfaces are machined. Then too, when the clearance between the guiding surfaces is greater than say 0.01 of an inch on a side (it is usually about 0.05 of an inch), it not infrequently happens that "binding", "galling", "chattering" and "hammering" of the gate in the body results, which tends materially to shorten the life of this type of valve causing it to leak and become unserviceable.

There is another undesirable result encountered with prior gate valve constructions. It has been practically impossible to standardize the valves so that their parts, their bodies, guides, bonnets etc., may be interchanged without difficult and expensive machining, fitting and adjusting of such parts each time a substitution is effected. As is well known, even under the best production methods practiced today, a greater amount of time and hand labor must be spent in fitting a particular gate in a particular body so that a perfect and a satisfactory fit is had between the seat surfaces of the gate and the corre-

100

sponding seat surfaces on the body seat rings.

It very seldom happens however that, when the fitting of the gate in the body has been completed, and the construction is such as to permit it, the gate may be swung around 5 180° on its vertical axis and replaced in the body or replaced therein with a proper working contact of the cooperative seat surfaces, and there is even less chance that a gate 10 will fit in any position with a proper working contact against the body ring seat surfaces in any other body than the one in which it has been initially fitted.

The net result of manufacturing gate 15 valves in this manner has been to increase their cost, well beyond what their cost should be, in order to absorb the costs of waste material, defective parts, etc., as well as to pay for a terrific amount of labor rendered necessary. Besides, each valve when finished is 20 a "handmade specialty", so to speak, and whenever such valve or one of its working parts becomes worn and must be renewed or replaced, it usually becomes necessary to re- 25 move the whole valve from the line and refit the worn part or fit a new part to the other parts, either on the premises or at the valve manufacturer's factory. In either case great inconvenience, delay and expense, 30 all of which might be saved if the valves and their parts could be standardized and made interchangeable, are often incurred.

With the present invention similar and 35 symmetrically disposed slots or grooves of great length in or along the interior walls of a hollow body, whether such body be a valve body or some other article, may be formed, milled, machined or finished, as the operation may be termed, with substantially 40 absolute precision, and quickly and cheaply, permitting standardization, reversibility and interchangeability of parts.

Accordingly, it becomes a primary object 45 of the invention to provide a machine with which one, two or more slots or grooves may be milled in or along the interior walls of a hollow body with the axis or axes of the slot, slots, groove or grooves, respectively, bearing a predetermined relationship to the 50 axis of or a plane through the body or to one another and, if desired, to a plane through or the surface of such body generally transverse to the longitudinal axis of its hollow interior, and a machine which will mill such 55 slots or grooves without variation from a fixed line of cutting regardless of the depth or length or other characteristic of the slots or grooves.

Another object is to provide in a milling 60 machine an arrangement whereby one or more long spindled cutters may be supported and braced at least adjacent the cutter teeth where the reaction from the cutting tending to bend, break or displace the spindle is 65 greatest, and an arrangement whereby two

or more milling cutters of the long spindle type may simultaneously be guided and supported during and throughout the entire extent of their distance of travel in working in a body of the character specified.

Another object of the invention is to provide a templet for cooperative use in combination with a cutting tool in connection with and as a part of the above mentioned machine and with a gate valve body or the like to permit the valve body to be rigidly secured and positioned with respect to the milling cutters whereby the guide slots or grooves in the valve body may be milled out or machined in such predetermined relationships, as above specified, and in the same relative predetermined relationships in successive valve bodies.

Many further objects, functions, uses and advantages of the invention, as well as the 85 novelties and uses of the preferred form illustrated, will be or should become clearly apparent after reading the following description and claims, and after viewing the drawings, in which:

Fig. 1 is a longitudinal vertical sectional view of one form of machine, templet and jig arrangement,

Fig. 2 is a top plan view taken on the line 2—2 of Fig. 1, the milling machine chuck being removed.

Fig. 3 is an end elevational view of the apparatus shown in Fig. 2 looking at the same from the right of Fig. 2,

Fig. 4 is a top plan view of the templet,

Fig. 5 is a front elevation of the templet, and

Fig. 6 is a section taken on the line 6—6 of Fig. 5.

In order to afford a better understanding of what may be said to be the primary purpose of my invention, that is, its use for cutting guide slots in the interior walls of a valve body chamber, a brief reference to the valve may not be amiss. The valve body generally designated 2 is to be provided with diametrically opposite guide slots or guideways 3 extending from the top or adjacent the top of the valve chamber to a place at or adjacent the bottom thereof, all of which is to be determined by the length of the guides or ribs on the gate, the extent of travel of the gate, the size, character and proportions of the valve body and gate, etc. The body, when initially cast, forged or otherwise formed, is preferably provided in the usual manner with its guide slots or guideways roughed out to oversize dimensions to permit finishing by machine to the proper or final dimensions required. After sandblasting or otherwise cleaning, the body is mounted in a lathe for the purpose of machining or finishing the bonnet abutment or connecting face or bonnet flange face 4, as it may be termed. This face must be machined off so that the plane there-

130

of will lie at a predetermined angle with respect to one or more planes of symmetry of parts of the interior of the body or to the axis of the body along which the valve gate will move. Generally and in the present instance, the plane of this surface will lie perpendicular to the axis of the body or valve chamber and to a plane of symmetry containing both the axis of the body and the axes or mean centers of curvature of the guideways, grooves or guide slots. Thus any two bodies of the same type and size will have similar bonnet abutment faces disposed in the same predetermined relation to other similar parts of those bodies.

The interior of the valve body illustrated is to be made symmetric insofar as the guideways and seats are concerned with respect to a plane to which the line of flow through the body is perpendicular. Likewise the gate for cooperation with the seats and guideways of the body is to be made symmetric insofar as the seat surfaces and guides are concerned with respect to the same plane to which the line of flow through the body is perpendicular. The plane to which reference is here made is that plane which contains the axis of the valve chamber and the axes or mean centers of curvature of the guide slots or grooves.

Following the finishing of the bonnet connection surface or face 4 the bonnet connection flange bolt holes through which the bolts pass to connect the bonnet through the body are located and drilled in predetermined positions and directions with respect to the approximate axes of the rough guideways. This may be done in any suitable manner, although I prefer to use a templet such as that described in my copending application Serial No. 268,484 above mentioned. This templet is similar to the templet to be described herein in that it may be a flat plate having a surface adapted to seat against the top finished surface of the bonnet connection flange, a pair of positioning lugs or pins adapted to be wedged into the top ends of the rough guide slots or grooves to position it approximately with respect thereto and a desired number of apertures through which the drills pass to drill the bolt holes. With such templet the bolt holes may be drilled through the flange of the body in predetermined positions with respect to the aforementioned planes of symmetry etc., and the body is now ready to have the guide slots or guide grooves milled out.

The milling machine in general comprises a relatively stationary chuck, generally designated 5, adapted to be attached in any suitable manner to a lathe, a drill press or other machine the head of which may be advanced or retracted, or depressed or raised, or which will permit the chuck 5 to be advanced or retracted, depressed or raised, as the case may be, a bearing carrying member or plate, gen-

erally designated 6, secured to the chuck 5 and to which the bearings for the spindles of the milling cutters are secured, a valve body positioning and securing templet, generally designated 7, which also supports or aids in supporting the milling cutters and their bearings during their cutting travel, and a jig or fixture comprising a skeleton frame structure, generally designated 8, in which the valve body or the like is supported and secured for the milling operation, as will more clearly appear. These parts, their construction, arrangement, functions and operations will be taken up specifically and in order as the description proceeds.

The chuck 5 comprises a casing 9 within which a drive shaft 11 is rotatably mounted for connection with any suitable source of power. A gear 12 secured to the shaft 11 meshes with gears 13 and 14, also suitably mounted for rotation in the casing 9, so that one of the last mentioned gears is driven in a clockwise direction and the other in an anti-clockwise direction to equalize the driving torque. Each of the gears 13 and 14 has a portion 15 projecting substantially through an aperture in the bottom of the casing of the chuck and each portion 15 is provided with a socket into which the Morse tapered ends 16 of milling cutter spindles 17 are received and secured against rotation. The spindles 17 are of sufficient length to extend the necessary distance into the body in which the milling operations are to be performed to obtain the full length of cut desired.

The plate 6 is secured to the chuck casing 5 in any suitable manner and is provided with apertures 18 through which rods 19 connected at one end to the templet 7 are adapted to pass with sufficient clearance to provide relative sliding movements, and with apertures 21 in actual alignment with the axes of the gears 13 and 14. Bushings 22 provided with bosses extending into the apertures 21 and internally threaded, as shown at 23, are secured to the plate 6 in any suitable manner. Long bearings 24 for the spindles 17 are provided with threaded portions 25 for engagement with the threads 23 in the bushings 22 and provide bearing areas for the spindles at 26 and 27, as will be noted by reference to Fig. 1, the latter bearing area being closely adjacent the milling cutters 28 removably secured on the lower ends of spindles 17. It is at once apparent that the bearing members 24 may be assembled upon the spindles 17, the cutters 28 secured to the ends of the spindles and the assembly secured to the chuck.

In order properly to support and brace the spindles and milling cutters against bending, breaking etc. which, because of the length of the spindles and the distance of the cutters 28 from their primary support in the chuck, are subject to the tremendous leverage when

in operation, the templet 7 between apertures 29 through which the milling cutters and their bearings are adapted to pass is provided with a rigid boss or projection 31 which, in the present instance, on opposite sides, is arranged to receive U-shaped guides 32 which are secured to it by a plurality of screws 33. The bearing members 24 have a sliding fit in the guides 32 and are adapted to travel up and down the same as the chuck head is raised and lowered. With this arrangement it is practically impossible for the cutters or spindles to give while the cutters are working.

The templet 7 not only serves to hold the milling cutter spindles and their bearings in proper alignment with one another and the cutters against any movement from their line of cutting, but also serves as a positioning and securing means for the valve or other body upon which the cutters are to operate. To this latter end its top and bottom faces 34 and 35, respectively, are planed off, the upper surface for cooperation with a part of the jig or fixture 8 and the lower surface to provide an abutment surface against which the finished surface 4 of the valve body bonnet connection flange is positioned. Two or more pins or plugs 36 projecting from the surface 35 of the templet are adapted to closely fit within bolt holes 37 drilled through the valve body bonnet connection flange to secure the body against lateral or rotative movements. The rods 19 are equipped at their upper ends with adjustable nuts 38 and lock nuts 39 for the purpose of raising the templet 7 and its connected parts to the upper limits of the jig or fixture 8 after the chuck and milling cutters have been raised a predetermined distance. Thus these mechanisms are cleared out of the way of the valve body so that the finished body may be removed and a second body inserted.

The jig or fixture 8, as above stated, includes a skeleton frame comprising a base 41, side members 42 preferably formed integral with the base, temporary valve body supporting plates 43 secured along the tops of the side members 42 and both jutting inwardly over the base 41, two pairs of brackets 44 secured to the sides 42 and to and between pairs of which rigid guide rods or bars 45 are secured, a pair of truss bars 46 each at its ends mounted on the rods 45 with a close but sliding fit thereabout, and a jack, generally designated 47, mounted on the base 41. Each truss rod or bar 46 is provided with a rib 48 the inner face 49 of which is machined to provide an abutment shoulder adapted to abut against one side of the templet 7, while the adjacent under face 51 of each truss bar 46 is likewise finished providing an abutment shoulder against which a portion of the top face of the templet 7 is adapted to abut. The jack 47, of course, has an adjustable head 52 raised or lowered through bevel gears 53 and

54 the latter of which is operated by a shaft 55 the outer end 56 to which a crank may be connected in any suitable manner.

In operation the chuck milling cutters and templet 7 being raised to their upper limits, the truss bars 46 being spread apart as wide as necessary to permit the templet 7 to be raised, and the head 52 of the jack being lowered, a valve body 2 is slid in perhaps from the right of Fig. 1 with its bonnet connection flange above the plates 43, as illustrated in Figs. 1 and 3. When the body has been set approximately in its proper position over the jack head and beneath the templet 7, the templet 7 is lowered a sufficient distance to permit the truss bars 46 to be brought together with their shoulders 49 against the sides of the templet, whereupon the jack is operated to carry the valve body upwardly until its upper surface 4 seats against the surface 35 with the pins 36 in the proper holes 37 and the top surface 34 of the templet 7 abuts tightly against the surfaces 51 of the truss bars 46. When the body has been thus centered and positioned the milling tools 90 may be fed downwardly into the body as fast as the kind of metal of the body and the cutters will permit. The cutting of two or more grooves progresses simultaneously and is therefore very speedy, and because of the 95 construction and arrangement above described, practically absolute accuracy is attained. When cutting guide grooves in a gate valve body of the character illustrated and described herein the axes of the slots or 100 grooves are absolutely parallel and can definitely be made to lie in a desired plane bearing a predetermined relationship to the surface 4 of the valve body bonnet connection flange.

While I have shown and described what is at present a preferred form of the invention and one of its uses, it will be understood and appreciated that many variations and modifications may be made therein by those skilled in the art without departing from the spirit 110 of the invention and the scope of the appended claims.

I claim:

1. A device of the character described comprising, means for positioning a hollow body having an opening between its exterior and interior, means rigidly secured to said positioning means adapted to project within said body through said opening when the body is positioned, a cutter spindle, a cutter thereon for operating upon the interior surface of said body, an elongated bearing for said cutter spindle and means on said rigidly secured means for guiding said spindle bearing when in the body.

2. A device of the character described comprising, a templet having a surface adapted to abut against the top surface of a valve body bonnet-connection flange, means for supporting a valve body against said surface,

5 a tool for operating upon the interior surface of said body and a projection on said templet adjacent said surface and adapted to extend into the valve body cavity, said projection having a guideway for guiding a tool into the valve body cavity.

3. A device of the character described comprising, a templet having surface areas against which the top surface of a valve body bonnet-connection flange may abut, means projecting from said surface for securing said flange against movements across said surface areas, a tool movable into a body supported on said templet and tool guide means 10 secured to said templet and adapted to project into the valve chamber of a valve body positioned against said surface to guide said tool into said body.

4. In a machine for milling a surface on 20 the interior of a hollow body, a milling tool, means for supporting and positioning the hollow body in operative relation to said tool, means for operating said tool, means for moving said tool along the surface that 25 is to be milled, and means secured relative to said supporting and positioning means for guiding and supporting said tool substantially over its entire length of movement along said surface.

30 5. In a milling machine in combination, a reciprocable chuck, a pair of milling cutters mounted in spaced relation in said chuck for rotation relative thereto and to one another, means cooperative with said chuck for securing an article having a relatively deep recess therein in such relation to said cutters that the lines of movement of said cutters when said chuck is reciprocated will be substantially parallel the line of depth 35 40 of the recess, and means cooperative with said article securing means for bracing said cutters substantially throughout the extent of their cutting movements.

6. In a milling machine, a reciprocably 45 mounted chuck, a pair of rotatable milling cutter spindles, each having a milling cutter secured to one end, rotatably mounted at their opposite ends in said chuck, bearings for supporting said spindles substantially 50 55 their full length and means relatively stationary with respect to said chuck and spindles for guiding said cutters, against the reaction caused by their engagement with the material being worked upon, substantially throughout the full extent of their working movements.

7. In combination with a tool holding 60 chuck and means for advancing said chuck, milling cutter spindles rotatably mounted at one end of each in said chuck, a milling cutter mounted on the opposite end of each spindle, there being a relatively great distance 65 between the milling cutters and said chuck, means secured to said chuck providing bearings for said spindles adjacent said cutters,

and means stationary relatively to said chuck for guiding said bearings during movements of said chuck.

8. A device of the character described comprising, a positioning member having a surface for positioning hollow bodies and the like placed thereagainst, means for supporting a hollow body against said surface, means rigidly secured to said member and positioned to project into a body supported 70 against said surface, a tool for operating upon the interior surface of a body supported against said surface, said tool being bodily movable with respect to an inner surface of 75 said hollow body and means associated with 80 said rigidly secured means for guiding a tool during its movements relatively to said body surface.

In witness of the foregoing I affix my signature.

VICTOR E. FLODIN.
